JEWELRY FINDING

Mario A. Caputo, 9 Cornerwood Court, Gaithersburg,
Md. 20760 and Hilda A. Valenta, 4601 Alcon Drive,
Camp Springs, Md. 20031

Filed June 18, 1973, Ser. No. 370,638

Term of patent 14 years

Int. Cl. D11—01

U.S. Cl. D45—19 S

FIG. 1

FIG. 5

FIG. 4

FIG. 4

FIG. 1 is a front elevational view of a jewelry finding showing our new design, the rear being identical;

FIG. 2 is a top plan view;

FIG. 3 is a bottom plan view;

FIG. 4 is a side elevational view; and

FIG. 5 is a sectional view taken along line 5—5 of FIG. 1.

We claim:

The ornamental design for the jewelry finding, as shown and described.
